DESIGN FOR A FAUCET STRAINER

Orloff W. Holden, Chicago, Ill., assignor to Knickerbocker Rubber Company, Chicago, Ill.,
a corporation of Illinois

Application February 6, 1941, Serial No. 98,794

Term of patent 14 years

To all whom it may concern:

Be it known that I, Orloff W. Holden, a citizen of the United States, residing at Chicago, in the county of Cook and State of Illinois, have invented a new, original, and ornamental Design for a Faucet Strainer, of which the following is a specification, reference being had to the accompanying drawing, forming a part thereof.

In the drawing:

Fig. 1 is a side elevational view of the faucet strainer, showing my new design;

Fig. 2 is a top plan view of the faucet strainer;
and

Fig. 3 is a bottom plan view of the faucet strainer.

I claim:

The ornamental design for a faucet strainer,
substantially as shown.

ORLOFF W. HOLDEN.
